UNITED STATES PATENT OFFICE.

GEORGE H. ECKMAN, OF SAN FRANCISCO, CALIFORNIA, ASSIGNOR OF ONE-HALF TO
WARREN Z. NEWTON.

SCREW-HOLDING DRIVER.

1,178,141.

Specification of Letters Patent. Patented Apr. 4, 1916.

Application filed May 14, 1915. Serial No. 28,093.

To all whom it may concern:

Be it known that I, GEORGE H. ECKMAN, a citizen of the United States, residing at San Francisco, in the county of San Francisco and State of California, have invented 5 a new and useful Screw-Holding Driver, of which the following is a specification.

This invention relates to improvements in screw drivers, and more particularly to 10 means for holding the screw in proper position at the end of the blade or shank without the necessity of holding or steadyng the screw by the hand of the operator.

Another object is to provide a screw-holding means which may be applied to an ordinary screw-driver, which is capable of being moved into or out of operative position thereon, and which is adapted to remain upon the shank of the driver whether 20 the holding device is being used or not.

While the present invention is designed more particularly for use by machinists, jewelers, or other workers in metal, it may, with equal facility, be advantageously used 25 in wood work where a bore or hole has not been previously provided, and is especially useful in driving screws in inconveniently located places.

A full and complete understanding of the 30 invention may be obtained from a careful consideration of the following detailed description, taken in conjunction with the accompanying drawings forming a part of this specification, it being understood that 35 while the drawing shows a practical form of the invention, the latter is not confined to strict conformity therewith, but may be changed or modified, so long as such changes or modifications mark no material departure from the salient features of the invention as pointed out in the claims hereto appended.

In the drawing, in which like reference characters designate corresponding parts in 45 each of the several figures: Figure 1 illustrates a screw driver, in elevation, having the device of the present invention applied thereto. Fig. 2 is a similar view of the lower portion of Fig. 1, but taken at right 50 angles thereto. Fig. 3 is a vertical longitudinal sectional view of Fig. 2, the screw-holding means being projected into position to hold a screw. Fig. 4 is an elevation of the device in engagement with the head 55 of a screw. Fig. 5 is a section on the line

5-5 of Fig. 4. Fig. 6 is a plan view of the blank before being formed into the device of the present invention. Fig. 7 is a view in elevation showing a modified form of the invention applied to the screw-driver. Fig. 8 is a view showing the manner of fastening the invention to the shank of the screw-driver. Fig. 9 is a view in elevation of the invention and disclosing in dotted lines the position which may be assumed by the attachment in engaging a screw. Fig. 10 is a view of the invention before it is applied, and Fig. 11 is a detail sectional view showing the attachment or engaging lugs on the shank of the screw driver.

Any ordinary screw driver is susceptible of having the present device applied thereto, the only alteration necessary being to provide a groove 1 in the shank 2 thereof in alinement with one face of the screw driver 75 blade 3, and a socket or indentation 4 in the opposite face 5 of the said blade.

The present invention comprises an attachment to be applied to the shank of the driver and having certain parts to co-act with the 80 said groove 1 and said indentation 4. To this end a blank is provided having a body portion 6 of rectangular formation, and preferably of a length approximately twice its width. This blank is adapted to be 85 formed of any suitable sheet metal, preferably steel, and is provided with an elongated tongue 7 extending from one of the long sides of the said body portion and in the exact center thereof, while the shorter ends are each provided with an outwardly 90 extending lug or projection 8 also preferably located centrally of the said shorter ends of the blank 6 and lying in a plane therewith. The relatively long tongue 7 is provided intermediate its length with a projecting lug 9, preferably formed by punching or pressing the metal of the said tongue outwardly from the opposite face thereof. 100 These features of the blank 6 are for a purpose hereinafter described, and it is to be understood that the size and proportions of the said blank depend upon the size of the screw driver to which the device is to be applied.

The device is applied to the screw driver by bending the body portion 6 around the shank 2 thereof to form a sleeve 10 with the ends having the lugs 8 abutting, and with the said lugs bent radially inward to 110

ward the center of the sleeve 10, thus formed, and extending into the groove or recess 1 provided at that point in the shank 2 of the screw driver. The faces of the 5 abutting lugs 8 are in alinement with the adjacent edges of the blank 6, and the groove 1 is of a length greater than the width of the lugs 8, thus permitting of a limited longitudinal movement of the applied device 10 upon the shank of the screw driver for a purpose to be explained. The tongue 7 is thus positioned upon the face 5 of the blade 3 of the screw driver with its free end 11 directed toward the active or driving end of 15 the blade, and the lug 9 in a position to contact with the socket 4 upon certain manipulations of the device along the shank of the screw driver.

When the device is pushed upwardly or 20 away from the active end of the blade to throw the same into inactive position, the lugs 8 contact with the upper end wall of the groove 1 (or that end farthest removed from the end of the blade), thus limiting 25 the movement of the holder in that direction. When in position the lug 9 fits within the socket 4 and tends to hold the device against dislodgment except when forced out of this 30 position by the operator, the normal tendency of the tongue 7 being to spring inwardly to tightly hug the face 5 of the blade 3.

When the operator forces the device into the operative position, the lugs 8 strike the opposite or lower end wall of the groove 1 which brings the lower edge 11 into exact alinement with the end of the blade 3 and prevents any further downward movement. When in this position, the lug 9 has been 35 forced out of the indentation 4 and bears against the face 5 of the blade 3 and tends to hold the lower edge 11 which is slightly beveled in spaced relation to the end of the blade, as shown in Fig. 3. This space is 40 sufficient to adapt the device to screws of varying sizes within certain limits.

To apply the device to a screw it is only necessary to introduce the end 11 of the tongue 7 into the notch of the screw, in a 45 somewhat angular position, when by forcing the said end 11 against the adjacent wall of the notch the same will yield sufficiently to permit of the active end of the blade of the screw driver being, in turn, seated in the 50 notch. When thus positioned, the lug 9, bearing against the blade 3, acts as a fulcrum and an outward pressure is exerted by the end of the tongue against the walls of the notch and thus maintains the screw 55 in proper position to be driven, as shown in Fig. 4 of the drawing.

In the modified form of the invention which is disclosed in Figs. 7, 8, 9, 10 and 11, the body portion 6 of the attachment is provided with a T shaped lug 12 at one end,

and a T shaped slot 13 at the other end, so that when the body portion is bent around the shank 2 the T shaped lug 12 may be sprung into the slot 13 for fastening the attachment to the shank. The shank 2 in this instance is preferably tapered with the larger portion at the lower terminal of the shank. 70

On the tongue 7 of the attachment ears 14 are formed which are adapted to be engaged by cam shaped lugs 15 formed on the blade 3 of the shank. The ears are located on the sides of the tongue 7, so that when the attachment is moved in one direction the ears will rest against the cam lugs 15 for holding the lower or working edge 11 of the tongue out of operative relation with the blade 3. When it is desired to have the tongue coöperate with the blade 3, the body 6 is moved downwardly causing the ears 14 to travel onto the lugs 15, as indicated in Fig. 11, so that the end 11 will be spaced from the blade 3 and in a position to be inserted into the notch of the screw. 75 80 85 90

What is claimed is:

1. A screw driver provided with screw-holding means consisting of a longitudinally movable member carried by the shank of the screw driver, means for limiting the inward and outward movement of the member along the shank, a spring tongue carried by the movable member with its free end adjacent the active end of the screw driver blade, and means for spacing said tongue from the blade when the movable member is in its operative position, so that the end of the tongue may coöperate with the end of the blade in holding the screw. 95 100 105

2. A screw-holding driver having a longitudinally movable member mounted upon the shank of the driver, a spring tongue carried by the member and adapted to lie parallel with the flat face of the screw driver blade, means for limiting the longitudinal movement of the movable member along the said shank, and means for holding the free end of said tongue in spaced relation with the active end of the blade, so as to coact therewith, the last mentioned means acting to maintain the holding member from movement when in its inoperative position. 110 115

3. In combination with a screw driver having a groove provided in its shank adjacent the blade thereof, and a socket provided on the blade, a sleeve surrounding the said shank having a lug projecting into the groove to limit the longitudinal movement of the sleeve upon the shank, and having a spring tongue provided with a lug intermediate its length, said lug being adapted, upon the shifting of the sleeve inwardly along the shank, to hold the device in its inoperative position, and when the device is moved in the opposite direction, to maintain the end of the tongue in spaced 120 125 130

relation with the end of the screw driver blade.

4. A screw driver provided on its shank with a longitudinally disposed groove, and on the opposite face of its blade with a socket, a longitudinally movable screw-holding member comprising a sleeve mounted upon the shank, having a lug adapted to ride in the said groove and to be limited in its movement thereby, and a longitudinally disposed spring tongue carried by the sleeve having its free or active end in alinement with and in spaced relation to the active end of the blade when in its operative position, a lug formed on the spring tongue intermediate its length and adapted to bear upon the adjacent face of the screw driver blade when in said position to maintain the said ends in spaced relation, said lug being adapted to enter the said socket when moved to lock the holding means in inoperative position.

5. A screw holding driver, carrying a longitudinally movable screw-holding member adapted to be held out of operative position upon the movement of said member in one direction, and means for causing, upon the movement of the member in the opposite direction, the active end of the holding member to align with and to be spaced away from the active end of the screw driver blade, in order to cause the free end of the said holding member to co-act therewith while under spring tension, and frictionally engage the notch in the head of a screw to hold or support the same.

In testimony, that I claim the foregoing as my own, I have hereto affixed my signature in the presence of two witnesses.

GEORGE H. ECKMAN.
